UNITED STATES PATENT OFFICE.

ALVA D. SUMNER, OF CHICAGO, ILLINOIS, ASSIGNOR TO ACORN BRASS MANUFACTURING COMPANY, OF CHICAGO, ILLINOIS.

HYDROCARBON-GAS GENERATOR.

No. 885,886.

Specification of Letters Patent.

Patented April 28, 1908.

Application filed May 28, 1906. Serial No. 319,160.

To all whom it may concern:

Be it known that I, ALVA D. SUMNER, a citizen of the United States of America, and a resident of Chicago, in the county of Cook 5 and State of Illinois, have invented certain new and useful Improvements in Hydrocarbon-Gas Generators, of which the following is a specification.

The main objects of this invention are to 10 provide an improved form of generating coil in which a large efficiency is produced by a comparatively small amount of heat; to provide an improved form of alcohol cup and burner; to provide an improved arrangement of valves for controlling the feed to the generator and avoiding the fluctuation in the gas pressure; and to provide for readily detaching the generator for the purpose of cleaning or to permit another to be 15 substituted. These objects are accomplished by the structure shown in the accompanying drawings, in which:

Figure 1 is a partly sectional front elevation of a gas generator constructed according 20 to this invention. Fig. 2 is a vertical section of the alcohol cup and burner.

In the structure shown, 1 represents the generator coil which is wound in the form of a hollow frustum of a cone. The upper end 25 of this coil is attached by means of a threaded connection 2, to the pipe 3 which leads to the mixing chamber 4. The lower end of the generator coil is attached by means of a threaded connection 5 to the threaded stem 6 which has therein the regulating needle 30 valve 7. The lower end of the generator pipe has rigid thereon a tapering head 8 which is held into a corresponding conical seat in the stem 6, by means of the threaded 35 connection 5. The connection at the upper end of the generator pipe is of similar structure. The stem 6 has a depending hollow nipple 9 which is threaded into the standard 40 10. The standard 10 is provided with a hollow cross arm 11 carrying a cutoff needle 45 valve 12 and having a threaded nipple 13 for attachment to the wire feed for the gasoline. The mixing chamber 4 is supported on the standard 14 by means of an upright pipe 15 50 which extends upwardly at the rear of the mixing chamber 4 and communicates with the same at 16. The lower end of the pipe 15 communicates with the burner 17 by means of the connection 18. The flow of gas from 55 the generating coil 1 into the mixing cham-

ber is controlled by means of the valve 19, below the air opening 20 at the lower end of the mixing chamber. The burner and alcohol cup are spun in two parts. The lower part 21 has a depending neck fitting in the 60 elbow 22 for supporting the burner. The upper part of the burner 17 extends downwardly to form an apron or flange which is spun into the form of an annular trough 23 for holding asbestos and alcohol or other inflammable material with which the generating coil is first heated. The burner 17 is depressed at its middle part 24 and the upper surrounding part is provided with a series of slots 25. The upwardly extending 70 flange on the member 21 fits tightly inside of the trough 23.

The operation of the device is as follows: The cutoff valve 12 is closed when the generator is first heated by means of a flame 75 from the alcohol cup or trough 23. The flame passes up within the generator 1 coming in contact with all of its coils and thoroughly heating the same. When the generator is sufficiently heated, the valve 12 80 will be fully opened to permit the desired flow of gasoline into the generator.

The special functions of the upper valve 7 are to regulate the admission of the liquid into the coil 1, and to prevent fluctuation of 85 the lights fed by the generator. It has been found in practice that, without the valve 7, the lights will fluctuate or pulsate at times caused by the gas backing into the supply pipe and the opposing pressures of said gas 90 and of the fuel feed. The orifice controlled by this valve is very small, and prevents backing of the gas into the tube 10 and connected pipe (not shown). The flow of the gas from the generator into the mixing tube 95 is controlled by means of the valve 19. Air enters the mixing chamber through the opening 20 and mixes with the gas in its passage upwardly through the chamber 4. The heat at the generator 1 causes a draft 100 upwardly through the generator and burner, and thus draws a small quantity of the gas from the mixing chamber through the connection 16 downwardly through the pipe 15 and elbow 22 into the burner 17. This gas 105 ignites at the burner, from the flame in the alcohol cup, and then continues to supply sufficient heat for the further generation of gas.

26 represents a bracket for supporting the 110

usual generator hood; said hood being omitted from the drawings for the sake of clearness of illustration.

When the generator coil becomes clogged, 5 the same may be readily removed by unscrewing the threaded connections 2 and 5 and another coil may be substituted while the first is being cleaned.

What I claim as my invention and desire 10 to secure by Letters Patent is:

1. In a gas generator, the combination of a continuously ascending generator coil, a member supporting the lower end of said coil and having a liquid-fuel receiving-chamber provided with independent inlet and discharge valves, said discharge valve supplying fuel to said generator, a mixing chamber at a higher level than said coil and receiving the hydro-carbon vapor therefrom, a burner 20 beneath said generator and a supply pipe connecting said mixing chamber with said burner.

2. In a gas generator, the combination of a continuously ascending generator coil, a 25 member supporting the lower end of said coil and having a liquid-fuel receiving-chamber provided with independent inlet and discharge valves, said discharge valve supplying fuel to said generator, a mixing chamber 30 at a higher level than said coil and receiving the hydro-carbon vapor therefrom, a burner beneath said generator, means for preheating said generator and a supply pipe connecting said mixing chamber with said 35 burner.

3. In a gas generator, the combination of a member having a chamber for receiving liquid hydro-carbon, independent inlet and discharge valves for said chamber, a gener-

ator adjacent to and supplied from said discharge valve, said generator comprising a continuously ascending pipe coiled into a substantially laterally closed frustum of a cone, a mixing chamber having its lower end above the level of the upper generator coil 45 and adapted to receive the combustible vapor therefrom, a heating burner beneath said generator, and a supply pipe connecting an intermediate point of said mixing chamber with said burner.

4. A gas generator comprising a continuously ascending pipe coiled into a substantially laterally closed frustum of a cone, a mixing chamber having its lower end above the level of the upper generator coil and 55 adapted to receive the combustible vapor therefrom, a heating burner beneath said generator and adapted to discharge a substantially continuous sheet of flame against the inside of the lowest coil, and a supply pipe 60 connecting said mixing chamber with said burner.

5. A gas generator comprising a continuously ascending pipe coiled into a substantially laterally closed frustum of a cone, a 65 mixing chamber having its lower end above the level of the upper generator coil and adapted to receive the combustible vapor therefrom, a heating burner beneath said generator, and a supply pipe connecting said 70 mixing chamber with said burner.

Signed at Chicago this 23rd day of May—
1906.

ALVA D. SUMNER.
